UNITED STATES PATENT OFFICE

CECIL M. WICKSTRUM, OF OMAHA, NEBRASKA

TENT-FRAME CONSTRUCTION

Application filed August 27, 1929. Serial No. 388,728.

This invention relates to tent frame construction, and more particularly to tent frames for tents known as chapel tents.

The primary object of the invention is to provide a tent frame which will be exceptionally large when extended, but when folded will provide a small and compact article which may be readily and easily handled and set up by a single person.

Another object of the invention is the provision of a frame of the chapel type including a flexible central bar adapted to bend to give the curved outline to the tent top when the connecting rods forming a part of the frame are hooked into the anchor disk of the frame.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view of a tent including a frame constructed in accordance with the invention.

Figure 2 is a sectional view through a tent and frame constructed in accordance with the invention.

Figure 3 is an enlarged detail view of the central connecting member of the frame.

Figure 4 is a sectional view taken on line 4-4 of Figure 3.

Figure 5 is a detail view of the main portion of the central connecting member of the frame.

Figure 6 is a fragmental detail view of one end of one of the flexible connecting bars of the frame.

Figure 7 is a sectional view through one of the supporting posts and connecting sockets.

Figure 8 is a sectional view taken on line 8-8 of Figure 7.

Figure 9 is a sectional view of a hinge connecting member between one of the cen-

tral brace rods of the frame and supporting post.

Figure 10 is a bottom plan view of the anchor disk of the frame.

Figure 11 is a sectional view taken on line 11-11 of Figure 10.

Figure 12 is a bottom plan view of the locking member used in connection with the anchor disk.

Figure 13 is a fragmental sectional view 30 through one of the extension bars of the tent.

Figure 14 is a fragmentary sectional view taken on line 14-14 of Figure 13.

Figure 15 is a sectional view taken on line 15-15 of Figure 13. 65

Figure 16 is a side elevational view of a socket member with which the extension arms are used.

Figure 17 is a side elevational view of an extension arm. 70

Figure 18 is a sectional view taken on line 18-18 of Figure 17.

Figure 19 is a bottom plan view of one of the extension sockets.

Referring to the drawings in detail, the tent frame includes a central section 5 which is provided with pairs of flanges 6 disposed at opposite sides thereof, each pair of flanges being provided with registering openings.

Supported between each pair of flanges, is a socket member 7 which is provided with a pair of ears 8 which are apertured to register with the openings in the flanges 6, for the reception of the pivot pins 9 that permit the socket members to swing inwardly, in a manner to be hereinafter more fully described. These socket members receive the inner ends of the flexible roof bars 10 which have their outer ends positioned in the sockets 11 of the corner sections, the corner sections including lower members 12, the members 11 and 12 being provided with ears 13 through which the tubular members 14 extend, the tubular members 14 providing pivots for the sections 11 and 12. 85

These tubular members 14 also provide supports for the outer ends of the anchor rods 15 that are shown as looped around the members 14. The inner ends of these anchored rods 15 are formed with hooks 16 that pass 90 95 100

into openings 17 of the anchor disk 18 mounted at the lower end of the rod 19 which has its upper end connected to the central section 5.

5 Thus it will be obvious that when the hooks 16 of the anchor rods 15 are positioned in the anchor disk 18, as shown by Figure 1 of the drawings, the flexible roof bars 10 are curved providing a frame which is substantially dome-like in formation. In order that the hooks 16 will be held against accidental displacement, a metal locking disk 26 is provided.

15 Fingers 27 extend from the locking disk 26 and are curved to engage the inner ends of the hooks 16, as shown by Figure 11 of the drawings, thereby locking the hooks in position.

20 The corner posts which are indicated by the reference character 19', are preferably hollow and fit over the spikes 20 that are driven into the ground surface to support the tent frame. Set screws such as indicated at 21 pass through the corner posts and engage 25 the spikes to secure the tent frame in position. An extension frame forms a part of the tent construction and includes socket members that are provided with upwardly extended end portions 29 which end portions 30 are provided with depending ears 30 formed at opposite sides thereof so that they may be positioned over the socket members 11 to receive the projected ends of the tubular members 14 in which the bolts 31 extend.

35 The extension arms which are indicated by the reference character 32, are formed preferably of channel bar material, and as shown have one of their respective ends positioned in the socket members associated therewith, 40 there being provided set screws 33 for securing the extension bars 32 in their proper positions. The outer ends of the extension arms 32 are curved downwardly as at 34, where they are provided with rollers 35 over 45 which the straps 36, carried by the tent covering extend, so that the tent covering may be secured to the extension arms.

50 These arms are provided with openings to receive hooks such as indicated at 37, that are carried by the guy ropes 38, to the end that the extension arms may be securely held against movement. The covering of the tent which is indicated by the reference character 22, is so constructed that it will extend over 55 the main portion of the frame of the tent, and will extend over the extension arms, the outer edges of the covering being curved as shown by Figure 13 of the drawings to fit over the curved ends of the extension arms.

50 As shown, the covering only extends a short distance beyond the ends of the downwardly curved portions of the extension arms, where the covering is provided with loop members 39 to receive the hooks 40 carried at the upper end of the side sections 41

of the tent. Owing to this construction, it will be obvious that the side walls of the tent may be supplied or removed at the will of the people using the tent.

I claim:

1. In a tent, roof bars, posts at the outer ends of the roof bars, socket members secured at the outer ends of the roof bars and extending laterally with respect to the posts, extension arms removably fitted in the socket members, and a cover for the frame. 70

2. In a tent, roof bars, socket members secured to the outer ends of the roof bars, extension arms disposed in the socket members, the outer ends of the extension arms being curved downwardly, and a cover for the frame. 80

3. In a tent, a frame including pivoted roof bars, extension arms removably secured to the outer ends of the roof bars, uprights 85 connected with the roof bars at the outer ends thereof to support the frame, and a covering for the frame.

4. In a tent, a frame including roof bars, rods connected with the roof bars at the outer ends thereof, an anchor disk having openings, hooks formed at the free ends of the rods and adapted to engage within the openings to hold the outer ends of the roof bars inwardly, and means for securing the hooks within the openings. 90

In testimony that I claim the foregoing as my own, I have hereto affixed my signature.

CECIL M. WICKSTRUM.
